[57] **CLAIM**

The ornamental design for a bottle, as shown and described.

DESCRIPTION

FIG. 1 is a perspective view of a bottle, showing my new design, the neck portion shown in phantom lines not being part of my design;

FIG. 2 is a front elevational view thereof, the rear elevational view being the mirror image thereof;

FIG. 3 is a right side elevational view thereof, the left side elevational view being the mirror image thereof;

FIG. 4 is a top plan view thereof;

FIG. 5 is a bottom plan view thereof;

FIG. 6 is a perspective view of a first alternative embodiment of my new design, the top and bottom views being the same as shown in FIGS. 4 and 5, respectively, and the right side and rear elevational views being respectively the same as the left side and front elevational views thereof;

FIG. 7 is a perspective view of a second alternative embodiment of my new design, the top and bottom views being the same as shown in FIGS. 4 and 5, respectively, and the right side and rear elevational views being respectively the same as the left side and front elevational views thereof; and,

FIG. 8 is a perspective view of a third alternative embodiment of my new design, the top and bottom views being the same as shown in FIGS. 4 and 5, respectively, and the right side and rear elevational views being respectively the same as the left side and front elevational views thereof.

The broken lines in the drawings are for illustrative purposes only and do not form part of the claimed design.
